(57) **CLAIM**

The ornamental design for a foldable mobile phone, as shown and described.

DESCRIPTION

FIG. 1 is a rear, left perspective view of a foldable mobile phone in a first folded state showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right perspective view thereof, shown in a second folded state;

FIG. 9 is a rear, left perspective view thereof, shown in the second folded state;

FIG. 10 is a front, right perspective view thereof, shown in a first unfolded state;

FIG. 11 is a rear, left perspective view thereof, shown in the first unfolded state;

FIG. 12 is a front, right perspective view thereof, shown in a second unfolded state;

FIG. 13 is a rear, left perspective view thereof, shown in the second unfolded state; and,

FIG. 14 is a front, right perspective view thereof, shown in a third unfolded state.

The broken lines in FIG. 7 illustrate portions of the foldable mobile phone that form no part of the claimed design.
